CLAIM

The ornamental design for a centrifugal compressor as shown and described.

DESCRIPTION

The patent or application file contains at least one drawing executed in color. Copies of this patent or patent application publication with color drawing(s) will be provided by the Office upon request and payment of the necessary fee.

1.Centrifugal compressor

1.1 : Front

1.2 : Back

1.3 : Left

1.4 : Right

1.5 : Top

1.6 : Bottom

1.7 : Perspective

**1 Claim, 7 Drawing Sheets
(7 of 7 Drawing Sheet(s) Filed in Color)**
